ATTORNEY

UNITED STATES PATENT OFFICE

99,651

DESIGN FOR A CONFECTIONERY PRODUCT

Norman M. Thomas, Brooklyn, N. Y., assignor to
Joe Lowe Corporation, New York, N. Y., a cor-
poration of Delaware

Application June 19, 1935, Serial No. 57,331

Term of patent 14 years

To all whom it may concern:

Be it known that I, Norman M. Thomas, a citizen of the United States and resident of Brooklyn, county of Kings and State of New York, have invented a new, original, and ornamental Design for a Confectionery Product, of which the following is a specification, reference being had to the accompanying drawing, forming part thereof.

Figure 1 is a front elevational view of a confectionery product showing my new design;

Figure 2 is a side elevational view of the confectionery product shown in Figure 1; and

Figure 3 is a top plan view of the confectionery product shown in Figure 1.

The design is characterized by its six downwardly sloping panel-like sides connecting a relatively small substantially hexagonal top with a relatively large octagonal base, the front and back faces being relatively wide and formed of pairs of adjacently disposed concave panels.

What I claim is:

The ornamental design for a confectionery product substantially as shown and described.

NORMAN M. THOMAS.
